United States Patent Office

Des. 211,661
Patented July 9, 1968

211,661

DRIVE STRAP

Bert E. Holub, 519 S. Main St., Sycamore, Ill. 60178

Filed Nov. 16, 1966, Ser. No. 4,698

Term of patent 14 years

(Cl. D54—9)

FIG.1

FIG.2

FIGURE 1 is a side elevational view of a drive strap;
and

FIGURE 2 is a bottom end view.

The dominant features reside in the solid line portion.

I claim:

The ornamental design for a drive strap, as shown and described.
